THREAD PACK AND METHOD OF AND MEANS FOR PREPARING THE SAME

**Heinrich Buddecke, Rheda (Westphalia),
Germany**

Application October 3, 1951, Serial No. 249,588

13 Claims. (Cl. 206—64)

13 Claims. (Cl. 206—64)

1

The invention refers to a yarn pack with the thread or yarn disposed in layers in back and forth arrangement, and separating sheets provided between the individual layers, as well as to a method of and means for preparing such thread packs.

In a known design of this type, the thread of each layer is in zig-zag or serpentine fashion. By reason of the manufacturing method of this type of construction with the aid of two series of pins around which the thread is slung back and forth, the two parts of the thread of a back and forth length are disposed apart from one another by at least the diameter of the pins employed. By reason of this, a comparatively large space is required for coiling thread of a definite length and from this results an excessive consumption of paper and the like for the thread pack and rather elevated cost in preparing the pack.

Spooling is comparatively difficult, time consuming and expensive. In addition, the thread is subjected to comparatively heavy strains through the forces active in the oscillating thread guiding mechanism. To maintain the thread pack in compact order causes certain difficulties, especially in the case of larger numbers of layers.

To avoid these shortcomings, the individual layers of threads, in accordance with the invention, are made up of flat longitudinal helicoidal windings disposed one above the other in more or less scale-like manner.

In this way, volume required is reduced considerably, it being a fraction only of what is needed with the known arrangement.

While, with the known arrangement, the rectangularly shaped separating leaves or strips are provided with a slit passage for the thread to pass on to the next following layer, the last portion of the thread of a layer, in accordance with the invention, contained within the frame-shaped separating leaf supporting the same, is passed on to the next following layer disposed thereto in crossed relation.

The separating leaves in the form of double strips are fastened with their ends to the strips of the preceding layer disposed crosswise thereto, or to the base plate, respectively, or glued thereto.

On the outside of the thread returns, distance strips have been provided corresponding in thickness to the thickness of the compressed thread layers. In this manner, the total thread thickness of the thread layers is equalized, in such a way, that the pack at its glued corners will not

present a reduced height but will rather form a uniform cube or a rectangular prism, in such a way, that any number of thread layers may be piled one above the other.

5 In accordance with the present invention, the method of preparing the novel thread pack consists in that each layer is formed by coiling the thread in helical fashion on a coiling mandrel of rectangular shape in longitudinal section, stripping the coil off and pressing the same flat simultaneously, in such a way, that the thread portion and the windings are in close contact and the coils are more or less superimposed in scale-like manner.

10

15. Further characteristics will become evident from the claims in connection with the following description.

The drawings show executions of the invention by way of example.

20 Fig. 1 showing a coiling mandrel for the preparation of the helicoidal windings in perspective.

Fig. 2 is a partial section through several layers of thread of the pack:

25 Fig. 3 is a front view;
Fig. 4 is a lateral view of the thread pack;

Fig. 5a and b show a separating strip with a distance strip in perspective view and in section.

30 Fig. 6 shows the skeleton of the thread pack composed of separating and distance strips in perspective view.

Fig. 7 is a lateral view of the pack with a wrapper.

35 Figs. 8 and 9 give views from above and laterally of another type of execution of the pack, and

Figs. 10 and 11 are perspective views of the pack with open lid.

40 pack with open end.

40 In order to give the yarn thread the shape of longitudinal helicoidal windings, thread 1, according to Fig. 1 is wound in a helicoidal line around a leaf-shaped coiling mandrel 2 or on correspondingly disposed tongs or bolts. In this manner, helicoidal windings with long parallelly extending lateral parts and rounded ends 7 are developed. The coil is then stripped off the mandrel and simultaneously compressed or pressed flat in such a way that the posture of the thread 50 3 of the coil such as shown in Fig. 2 is developed in which the individual helicoidal windings are superimposing one another in scale-like fashion.

In doing so, the distance between the two
55 thread parts of a winding may be selected in such

a way that the reciprocal superposition of the helicoidal windings may be of larger or smaller extent. In an extreme case, the two thread parts of a helicoidal winding may extend in an identical plane in close relation to one another.

On the layer of thread 3 considered here, an additional layer of thread 4 (Fig. 2) is placed which, however, extends vertically or at any other desired angle as regards the direction of the thread relative to thread layer 3. Additional thread layers follow above in such a way that each layer of thread is displaced by .90 degrees with regard to the layer of thread next below.

Between the individual layers of thread frame-like separating leaves 5 are disposed in the manner illustrated in Fig. 3. The central part of the thread layers is freely displayed within gap 6 of the frame while turns 7 of the thread are held individually between separating frames 5. The pressure under which the thread turns are held together is calculated such that it will not change the structure of the thread with any detrimental effect. This pressure is exerted by the thin freely extending edge of separating leaf 8.

Separating frame 5 is preferentially formed by separating strips 8 (Fig. 5) of which two only are required for each layer of thread, in such a way, that by layers a vertically and a horizontally disposed pair of separating strips 8 will be utilized. These separating strips are interunited in suitable manner at their corner faces 10 to the extent they are situated without thread returns 7, for instance by stitching with wire. Preferentially, union is effected by pasting or glueing.

To avoid that the corner portions of the thread pack, by reason of the intermission of the thread layers be more reduced in height than the intermediate part, special distance strips 9 (Fig. 5) are also inserted, being disposed without thread returns 7. The thickness of the distance strips corresponds to the thickness of the compressed layers of thread.

By this procedure, a uniform thickness all round of the thread pack is obtained, and a less handsome falling-off of their thickness toward the corners or toward the exterior, respectively, is avoided so that a firm seating of the thread layers is not impeded, with the result that contrary to the arrangements known so far, an unlimited number of layers may be piled up.

The portion of the separating strips 8 covering the thread returns is roughened or perforated for the purpose of obtaining a firmer grip.

The distance strips 9 are stuck to separating strips 8 and provided with incisions, notches or slots 20 to make it possible to coil a plurality of such strips as a continuous band in a roll. In preparing the separating frame 5, strips of the required length are cut off by hand.

By the layer-wise alternating positioning of a double strip 8, 9 each lengthwise and crosswise, and the union of the corner portions, a skeleton 11 of the form shown in Fig. 6 is developed.

The layers of thread inserted simultaneously with the building-up of the body of the skeleton by the consecutive glueing-on of the double strips 8, 9 are connected with one another at one corner each or at corners opposing one another. This connection is effected in accordance with Figure 3 by a thread portion 12 of the last thread return 7 of the thread layer which is passed through frame opening 6 below the covering separating strip 8 toward above across the transversely extending separating strip 8 toward the next following layer of thread.

The individual helicoidal windings are disposed within the thread layers in such a way that by withdrawing the thread in the direction of arrow 13 (Fig. 2), the helicoidal winding happening to be uppermost of the thread layer is taken off while the ones following below are being detained at the thread returns. After the last winding has been withdrawn, the next layer of thread following below is extracted in identical manner.

The finished thread pack which at the bottom is provided with a closed base plate 14 (Fig. 4) is provided at the top preferentially with a wholly or partly transparent covering plate 15 (Fig. 7) which, in its center, has a hole 16 through which thread 1 is passed toward the outside. The complete pack is enclosed in a wrapper 17 of paper or the like whose edge portions extend over covering plate 15 and are glued to the latter. By preference, opening 16 of the non-transparent covering plate 15 is covered by a cellulose foil on whose lower face thread end 1 is attached by pressure and under heat, the thread having at its extreme end a loop 18 of cellulose foil or the like by which it may be extracted in conjunction with the thread end through opening 16.

It goes without saying that any other type or form of packing such as a case or box (Figs. 10 and 11) may as well be used, such packing being designed in such a way, if desired, that the emptied thread pack may be replaced by a filled one.

In place of the thread pack of rectangular-prismatic or cube shape, any other prismatic or cylindrical form may be employed, the individual pairs of strips receiving by layers a corresponding angular twist. In place of paper or cardboard any other suitable material may be employed in the construction of skeleton body 11, such as wood or Bakelite, and the skeleton body may also be designed in such a way that it may be taken asunder for the purpose of replenishing with thread.

The thread pack described is suitable for any kind of thread, i. e. from the finest silk thread to the rough binding twine for agricultural purposes. It may be employed also for the ropes of parachutes, of harpoons and ship saving rocket apparatus.

In the simplified form of the thread pack according to Figs. 8 and 9 used for instance for skeins of wool or silk of reduced thread length, only the one end 19 of the helicoidal windings of the thread is held together by separating leaves. Separating leaf 21 used in this case is folded zig-zag, and the individual layers of thread are 55 inserted in the folds open toward one side.

The point of insertion is held together by a strip of paper 22, or the like. The free portion of the thread 23 is covered by a transparent wrapper 24 which at its free end is provided with a discharge opening 25 for the thread.

The separating leaves placed between the individual thread layers may also be extended up to the free end of the pack.

As has been demonstrated by tests, with this type of thread pack also the thread may be withdrawn to the very last bit without any felting becoming apparent.

Thread packs of the type described may be provided at their bottom with suitable retaining means such as a drawing-pin 26 (Fig. 11), an adhesive edge, a suction-disc or a magnet by which the pack may be fixed at the point of employment. The pack or its casing may be 70 provided with a cutter 27 (Fig. 10) for the pur-

pose of separating any length of thread desired.

What is claimed as new is:

1. In a thread pack of the class described flat thread layers superpositioned one above the other, each consisting of one strip of flat pressed longitudinal helicoidal windings, said windings being arranged in overlapped scale like fashion within their layers, a pair of spaced separating leaves between every two adjoining layers, each leaf being positioned along a return bend portion of the winding of each layer and directly contacting said portion and separating it from adjoining layers, in order to prevent any entanglement of the thread and to enable a thread-connection between adjoining layers within the area of the layers, and means to hold together said layers and leaves.

2. In a thread pack according to claim 1, said separating leaves being frame-like in fashion, and the last thread winding of every layer passing, within the opening of the separating leaves, over to the first winding of the following layer the thread-windings of which being arranged crosswise thereto.

3. In a thread pack according to claim 1, said separating leaves being composed each of two strips, the strips of each separating leaf being disposed crosswise to the strips of the following separating leaf and having its corners glued thereto.

4. In a thread pack according to claim 1, said separating leaves being frame like in fashion, and being composed each of two strips, an inner portion of the strips extending over the returns of the thread-windings on each side, said portions being roughened or perforated.

5. In a thread pack according to claim 1, and distance strips having a thickness equal to that of the compressed thread layers, and being disposed between said separating leaves out of the reach of the returns of the thread windings.

6. In a thread pack according to claim 1, said separating leaves being composed each of two strips, distance strips having a thickness equal to that of the compressed thread layers and being disposed between said separating leaves out of the reach of the returns of the thread windings, each strip of a separating leaf forming a unit with its distance strip.

7. In a thread pack according to claim 1, said separating leaves being composed each of two strips, distance strips having a thickness equal to that of the compressed thread layer, each strip of a separating leaf forming a unit with its distance strip, a plurality of united strips being interconnected in band like fashion, slits or notches at short intervals in said distance

strips enabling said interconnected strips being rolled up.

8. In a thread pack according to claim 1, and a wrapper of paper-like material enclosing bottom and sides of the pack, a covering plate, upper edges of the wrapper gripping over said covering plate, and a thread discharge hole in said covering plate.

9. In a thread pack according to claim 1, said means for holding together said layers and leaves being arranged only on the one end of the windings while the other end in whose direction the thread is pulled out being left free.

10. In a thread pack according to claim 1, said separating leaves consisting of a zig-zag folded strip separating the layers on the one end of their windings, a band shaped means adapted for holding together said layers and folded strip, a cover made of transparent material covering the other end of the layers, an opening in said cover through which the thread can be pulled out.

11. In a thread pack according to claim 1, a receptacle enclosing the thread pack adapted for being opened in order to replace the thread pack, and a discharge opening in a wall of said receptacle for the thread.

12. In a thread pack according to claim 1, and retaining and fastening means adapted to station the pack in its position of use.

13. In a thread pack according to claim 1, a wrapper of paper-like material enclosing bottom and sides of the pack, a covering plate, upper edges of the wrapper gripping over said covering plate, an opening in said covering plate, a piece of cellulose foil closing said opening and having to its lower side the thread affixed, and a loop being attached to the upper face of said cellulose foil enabling the foil together with the thread being pulled out.
